UNITED STATES PATENT OFFICE.

HARRY WARSHILSKY, OF CHICAGO, ILLINOIS, ASSIGNOR TO E. GOLDMAN & COMPANY, OF CHICAGO, ILLINOIS, A CORPORATION OF ILLINOIS.

BOTTLE-WASHER BRUSH.

No. 872,596.

Specification of Letters Patent.

Patented Dec. 3, 1907.

Application filed June 5, 1907. Serial No. 377,296.

To all whom it may concern:

Be it known that I, HARRY WARSHILSKY, a subject of the Emperor of Germany, residing at Chicago, in the county of Cook and State of Illinois, have invented a new and useful Improvement in Bottle-Washer Brushes, of which the following is a specification.

My invention relates to an improvement 10 in the class of brushes for scouring the interiors of bottles in a bottle-washing machine, such for example as that shown and described in Letters Patent of the United States No. 827,388, dated July 31st, 1906.

15 The primary object of my invention is to provide a novel construction of brush-device which is adapted, more particularly, for scouring the interior of a bottle-bottom of irregular shape, such as a champagne-bottle, 20 although my improved brush is also adapted for use in scouring other forms of bottles, because of the large number of bristles which the construction of the ferrule enables to be drawn into it, whereby it is rendered a very 25 effective inside bottom-brush for bottles of all kinds.

In the accompanying drawing, Figure 1 shows my improved brush-device by a view in elevation; Fig. 2 shows the same by an enlarged view in vertical sectional elevation, 30 the section being taken at the line 2 on Fig. 3 and viewed in the direction of the arrow, and Fig. 3, a section taken at the line 3 on Fig. 1, viewed in the direction of the arrow, and enlarged.

The brush-head shown at 4, formed preferably of brass, is on the end of a ferrule 5, of the same metal, internally threaded at its lower end to adapt it to screw on the end of 40 its carrying-stem (not shown) in a bottle-washing machine. While it is practicable to form the head and ferrule integral with each other, it is more desirable to form them as separate parts, adapting the head to be 45 screwed on a reduced end of the ferrule, as shown in Fig. 2. The upper end of the ferrule is solid and contains a discharge-opening 6. The head 4 is solid beyond a chamber 7 formed therein in advance of the nut-portion 50 8 about the base which screws on the ferrule, the chamber having outlets 9, 10, in the wall of the head, which may extend in different directions to discharge accordingly in the interior of a bottle into which the brush is introduced. A plurality of openings 11, of

which four are shown in the drawings, are formed longitudinally through the solid portion of the head about its center, at which a discharge-opening 12 may be provided. The brush-material 13 (preferably bristles) 60 is provided in separate bunches or tufts 14, each bound at its inner end to expand at its outer end and to adapt the bound end to be inserted into an opening 11; and the binding wires for the tufts are fastened together in 65 the hollow base of the head to unite them and secure them firmly in place.

Of course, as will be understood, while four of the openings 11 are provided in the head, this number may be increased or decreased 70 where it is desired to provide a larger number of tufts for producing a thicker brush, or a smaller number of tufts for producing a thinner brush. When the brush-material is worn out with use, it may be readily withdrawn from the head, on severing the wires which bind the inner ends of the tufts together, and new tufts may be inserted in their place and fastened in the head. As will also be understood, the holes 11 may extend at any suitable angles to produce desired spreading of the tufts where each is composed of a large number of bristles. The rounded shape shown of the base of the head 4 is desirable, since it is thereby rendered less liable to injure a bottle-neck in being withdrawn therefrom.

Where the head and ferrule are formed, as preferred, in separate parts, the head, since it is a comparatively inexpensive part, may 90 be discarded with the worn out brush to be supplanted on the ferrule with a new head equipped with the bristles, thereby enabling the ferrule to be a permanent part of the machine. The chamber in the head forms a 95 reservoir for the cleansing water and the outlets from this chamber serve to direct the water against all parts of the interior walls of the bottle while the brush is scouring the bottom thereof.

The shape of the brush produced by the peculiar connection of the brush-material with the head, particularly adapts it to work between the bottle-wall and depression in the bottle-base, such as is provided in champagne and other bottles, and thus thoroughly scour such regular bottoms of the bottles. The central opening 12 in the head supplements the openings 11 in supplying the cleansing water to the brush-material.

110

What I claim as new and desire to secure by Letters Patent is—

1. A brush-device for bottle-washing machines, comprising, in combination, a ferrule adapted to be connected at one end with its carrying-stem on a bottle-washing machine and having a reduced threaded section on its opposite end, a brush-head having its base formed with a nut-portion at which it screws on said reduced ferrule-section, said head containing longitudinal openings inclined to its axis, and tufts of brush-material confined in said openings to extend spreadingly from the head and fastened together at their inner ends.
2. A bottle-washer brush-device comprising, in combination, a ferrule having a solid

externally threaded end-portion containing a discharge-opening, a head having a nut-portion on one end at which it is screwed upon said threaded ferrule, and provided with longitudinal openings in its solid outer-end portion with an interposed chamber having discharge outlets extending at varying angles through the wall of the head, tufts of brush-material fastened in said openings to extend spreadingly from the head, and a central discharge-opening in the solid portion of said head.

HARRY WARSHILSKY.
